JOSEPH ALBERT RONCHETTI, OF WOONSOCKET, RHODE ISLAND, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,170,995.

Specification of Letters Patent. Patented Feb. 8, 1916.

Application filed June 5, 1908. Serial No. 436,744.

To all whom it may concern:

Be it known that I, JOSEPH A. RONCHETTI, a subject of the King of Italy, residing at Woonsocket, in the county of Providence and State of Rhode Island, have invented 5 certain new and useful Improvements in Type-Writing Machines, of which the following is a full, clear, and exact description, such as will enable others skilled in the art 10 to which it appertains to make and use the same.

This invention relates to typewriting machines and more particularly to the key actions thereof.

15 One of the objects of the invention is to provide means of improved construction for returning the key levers to normal positions after depression.

Another object is to provide a fulcrum for 20 the key-levers of typewriting machines such that the key-levers while normally locked against accidental dislodgment may be readily removed from the fulcrum when desired.

Another object is to provide means where- 25 by key-levers of unequal length which are mounted upon the common fulcrum may have equal dips.

A further object is to provide improve- 30 ments generally in the key-actions of type-writing machines.

Other objects will be in part obvious and in part pointed out hereinafter.

The invention accordingly consists in the features of construction, combinations of 35 elements and arrangement of parts which will be exemplified in the construction hereinafter set forth, and the scope of the application of which will be indicated in the following claims.

40 In the accompanying drawing wherein is illustrated one of the various possible embodiments of my invention, Figure 1 is a view in plan thereof. Fig. 2 is a view taken longitudinally through a portion of a type-writing machine, the mechanism constituting 45 my invention being shown in elevation. Fig. 3 is a view taken substantially on the line 3—3 of Fig. 2 looking in the direction of the arrow. Fig. 4 is a detached view of a portion of one key-lever in a different position, showing the manner in which it is normally locked against removal. Fig. 5 is a 50 sectional view taken substantially on the

line 5—5 of Fig. 2, looking in the direction of the arrow. 55

Similar reference characters refer to similar parts throughout the several views of the drawing.

Referring now to the drawing, 1 denotes a portion of the framing of the machine, 60 across the rear lower portion of which is extended a fulcrum-bar 2, said bar being suitably supported at its ends in the framework of the machine. This bar is provided with a depending knife-edge portion 3, which forms 65 a common pivot for each of the key levers of several banks, individual key levers of each of the banks being shown at 4, 5 and 6 respectively. The key levers of each bank are of a length different from those of the 70 others thereof as shown in Figs. 1 and 2, and each key lever at its rear end is slightly offset as at 7, said offset portion being provided with a slot 8, substantially V shaped as shown, which receives the knife edge 3 of 75 the fulcrum bar.

10 represents a slotted comb member, which is secured to the fulcrum-bar 2 as by means of screws, one of which is shown at 11 and is also supported at its ends in 80 the framework of the machine. The type bars pass through the slots 12 of this comb-member and the distance between knife edge 3 and the bottom walls of the slots is some- 85 what less than the height of the end 14 of the key lever at either side of the V-shaped slot 8.

Each of the key levers is held in normal position and returned to such position after depression by means of a bent spring 15, the 90 upper end of which is bent downward as at 16 and then extended through an eye 17 formed in the key lever, the outer end 18 of said spring being bent back in the direction of the curved portion of the spring, and 95 engages the side of the key lever. By means of this construction, the several springs are maintained in parallelism with their key levers, said key levers and said springs lying in adjacency. The opposite end of each of 100 springs 15 is supported upon an adjusting screw 20, which is threaded in a forward extension 21 of the comb member 10. Through a manipulation of these adjusting screws, 105 the springs may be given any desired degree of tension, as will be obvious.

It will be noted that the springs 15 hold the fulcrum parts of the key levers in engagement with the knife point 3 of the fulcrum bar 2, and also operate to return the 5 key levers to, and hold them in, their normal positions after depression.

In order to give the key levers 4, 5 and 6, which constitute individual members of the three different banks, the same amount of 10 dip when depressed, key lever 4, which is a member of the bank having the levers of the greatest length is rested directly upon the universal bar 22, the latter being suspended by means of links 23, upon arms 15 24, mounted upon a universal rock-shaft 25. The key lever 5 of the middle bank approaches the universal bar as far as the point indicated by the line *a*, and the key lever 6 of the bank having the keys of the 20 shortest length approaches the universal bar as far as the line *b*. Therefore, the key levers 5 and 6, move slightly before they engage the universal bar, the construction being such that the dip of all the key levers 25 in the several banks will be equal and the stroke of the universal bar will be the same when any of the several levers is depressed.

In order to equalize the "feel" upon the several key levers, leaf springs 26 and 27 are 30 introduced between the key levers 5 and 6 of the middle and upper banks, which are spaced from the universal bar, each of the several springs being fastened to its key lever as at 28, the end of the spring resting 35 upon the universal bar. During the downward movement of the key levers equipped with such springs, said springs will ultimately be collapsed against the surfaces 30 and 31 of the key levers.

40 As will be observed from the above description, the several key levers are held against their fulcrum, which is constituted in the present instance by the knife edge 3, by means of the spring 15. Consequently, if 45 any of the key levers should be pushed backward or forward, as shown in Fig. 4, the walls of the V-shaped slot 8 will abut the knife edge and the bottom 32 of the key lever will abut the bottom wall 13 of one of 50 the slots 12. It will therefore be impossible unintentionally to remove the key levers from their fulcrum when they occupy either a normal or a depressed position, or any position between said two positions. When, 55 however, any one of the key levers is swung to the position illustrated in the dotted lines in Fig. 1, said key lever may be withdrawn from between the comb 10 and the fulcrum bar 2.

60 It will accordingly be seen that I have provided a construction well adapted to attain, among others, the several ends and objects above enumerated, in a simple yet efficient manner. While the key levers 65 are normally locked against removal, they

may be removed with great facility when desired. Another advantage inherent in the construction is the simplicity of the returning spring structure and the manner in which individual springs are always maintained in their proper position adjacent the key levers. The spacing of the middle and upper banks of keys from the universal bar also provides for an equal dip 70 for each key lever when depressed, and the "feel" of the several keys is equalized by 75 means of the springs which are introduced between the middle and upper banks of keys.

In order to remove any chance of ambiguity occurring in this specification or in the claims, it may here be noted that by the term "dip" is meant the distance traveled by the key end of each of the key levers when depressed to effect printing, and by 80 the term "feel" is meant the character or quality of the resistance offered by the key levers to depression.

As many changes could be made in the above construction and many apparently 90 widely different embodiments of this invention could be made without departing from the scope thereof, it is intended that all matter contained in the above description or shown in the accompanying drawings 95 shall be interpreted as illustrative and not in a limiting sense.

Having described my invention, what I claim as new and desire to secure by Letters Patent, is:—

1. In a typewriting machine, the combination with a key lever, of a fulcrum for the same, means for returning the key lever to normal position after depression comprising a curved spring extended through an 105 eye provided in the key lever and having a portion thereof engaging the side of the key lever, whereby said spring is maintained in position adjacent the key lever, and an adjustable support for said spring 110 suspended from said fulcrum.

2. In a typewriting machine, the combination with the key-levers having holes therein, of a fulcrum for said key-levers, and means for maintaining the key-levers in engagement with said fulcrum and for returning them to normal position after depression, comprising curved springs, one end of each of which is supported from said fulcrum and the opposite end is passed through the hole in said key-lever and bent in a direction to lie in a plane parallel with the plane of the body of said spring against the opposite side of said key-lever, so as to hold the key-lever and said spring in operative relation.

3. In a typewriting machine, the combination with the key levers and a fulcrum therefor, of a curved spring arranged in parallel relation with each of said key levers, each 125

of said key levers being provided with an eye through which one end of the spring extends, an adjusting screw for supporting the other end of said spring and a support suspended from said fulcrum in which the adjusting screw is mounted.

5. In a typewriting machine, the combination with the key-levers, of a fulcrum therefor, curved springs the body portion of each 10 of which lies in a plane in parallel relation with each of said key-levers, each of said key-levers being provided with a hole through which one end of the spring extends, an adjustable screw for supporting 15 the other end of said spring, and a support suspended from said fulcrum in which the adjusting screw is mounted.

6. In a typewriting machine, the combination with the key levers, of a fulcrum therefor, springs for holding the key levers in engagement with their fulcrum, and means mounted on said fulcrum for holding the key levers against removal when in their 20 normal positions but which permits their 25 removal when they are moved upward from their normal positions.

7. In a typewriting machine, the combination with the key levers, of a knife-edge fulcrum therefor, springs for holding said levers in engagement with their fulcrum, and means disposed beneath the key levers and suspended from said fulcrum which coöperates therewith to prevent the removal of the key levers when they occupy their 30 normal position, but which permits the removal of the key levers when they are swung upward from their normal positions.

8. In a typewriting machine, the combination with the key levers, of a depending 40 knife-edge fulcrum therefor, spring means for maintaining the key levers in engagement with said fulcrum, and a member suspended from said fulcrum disposed beneath the key levers adjacent their fulcrum points 45 and extending in parallel relation with said fulcrum, which coöperates therewith to prevent a removal of the key levers when they occupy their normal positions, but which permits said key levers to be withdrawn 50 from their fulcrum when they are swung upward from normal position.

9. In a typewriting machine, the combina- 55 tion with the key levers, of a fulcrum bar having a depending knife edge with which 60 said key levers engage and which forms a fulcrum therefor, and a slotted member arranged adjacent said bar through which the ends of said key levers extend, said slotted member and said fulcrum bar coöperating 65 to lock the key levers against removal when the same are in normal or depressed positions, but permitting the key levers to be withdrawn when they are swung to positions above their normal positions.

10. In a typewriting machine, the combina- 70

tion with the key levers, the fulcrum end of each of which is provided with a V-shaped slot, of a fulcrum bar having a depending knife-edge portion which enters the slots of said key levers, a slotted comb member suitably supported adjacent said fulcrum bar through the slots of which the key levers extend, the slots of said comb member operating as guides for the key levers and said comb member coöperating with 75 said fulcrum bar to prevent the removal of the key levers when they occupy their normal positions, but permitting the removal thereof when they are swung upward from their normal positions, and a spring engaging each of the key levers and maintaining it 80 in engagement with its fulcrum.

11. In a typewriting machine, the combination with the universal bar, of key levers arranged above the same, and springs interposed between the key levers and the 85 universal bar.

12. In a typewriting machine, the combination with the universal bar, of a plurality of banks of key levers, the key levers of each 90 bank differing in length from those of the other banks, and springs interposed between the key levers of certain of said banks and the universal bar.

13. In a typewriting machine, the combination with the universal bar, of a plurality of banks of key levers extending across the universal bar above the same, the key levers constituting one of said banks resting upon the universal bar and the key levers constituting the other of said banks being spaced from said universal bar, and springs interposed between the key levers of said last-mentioned banks and the universal bar.

14. In a typewriting machine, the combination with the universal bar, of a plurality of banks of key levers, each bank being constituted by key levers of equal length but of a length differing from those of the other banks, the key levers of one of said banks resting upon the universal bar and those of the other or others of said banks being raised above said universal bar, and a spring interposed between the key levers of each of said last-mentioned bank or banks and the universal bar.

15. In a typewriting machine, the combination with the universal bar, of a plurality of key levers disposed above the same, certain of said key levers resting upon the universal bar and others thereof being out of contact therewith, and equalizing springs interposed between such of said levers as are out of contact with the universal bar.

16. In a typewriting machine, the combination with the universal bar, of a plurality of banks of key levers disposed above the universal bar, the key levers constituting each bank differing in length from those 130

of the others of said banks, a common fulcrum for said key levers, the key levers of one of said banks resting upon the universal bar and those of the other banks being out 5 of contact therewith, and a spring attached to each key lever of said last mentioned banks and interposed between the same and the universal bar.

16. In a typewriting machine the combination with the universal bar, of a plurality of banks of key levers disposed above the universal bar, the key levers constituting each bank being of an equal length but of a length different from those of the others of 15 said banks, and spring means for equalizing the dips of each of said key levers.

17. In a typewriting machine the combination with the universal bar, of a plurality of banks of key levers disposed above the 20 universal bar, the key levers of one of said banks resting upon the universal bar, and those of the other banks being out of contact therewith, and means for equalizing the feel of said key levers when they are 25 depressed.

18. In a typewriting machine, the combination with the universal bar, of a plurality of banks of key levers disposed above the universal bar, the key levers constituting 30 each bank being equal in length but of a length differing from those of the others of said banks, a common fulcrum for said key levers, the key levers of one of said banks resting upon the universal bar and those of 35 the other banks being out of contact therewith and spaced such distance therefrom as will give each of the key levers of the several banks an equal dip, and means for equalizing the feel of said key levers when they are 40 depressed to effect printing.

19. In a typewriting machine, the combination with a universal bar and a plurality of key levers disposed above the same, one of said key levers being in contact with said 45 universal bar and another of said key levers being disposed above and out of contact with said universal bar, and resilient means between said second mentioned key lever and said universal bar whereby the dips of each 50 of said key levers is equalized.

20. In a typewriting machine, the combination with the key levers, of a fulcrum therefor, springs for holding said key levers upwardly against said fulcrum, and means 55 supporting said springs at one end from beneath the fulcrum, each of said springs being curved in the direction of its length and having its opposite end bent backwardly upon itself in a manner to engage both sides 60 of said key lever to prevent a tilting motion thereof.

21. In a typewriting machine, the combi-

nation with the key levers, of a fulcrum therefor, a comb through which the ends of said levers pass co-acting with said fulcrum 65 to hold the key levers in place and means preventing a downward movement of said key-levers to remove the same.

22. In a typewriting machine, the combination with the key levers, of a fulcrum therefor, an inverted comb member co-acting 70 with said fulcrum to hold said key levers in place, and the spring means intermediate said comb member and said key levers for returning the latter to normal position. 75

23. In a typewriting machine, the combination with the key levers, of a fulcrum bar having a depending knife edge with which said key levers engage and which forms a fulcrum therefor, spring means for holding 80 said key levers against said fulcrum, and a slotted member arranged adjacent said bar through which the ends of said levers extend, said slotted member and said fulcrum bar co-operating to lock the key levers 85 against removal when the same are in normal or depressed positions, but permitting the key levers to be removed when they are swung to positions above their normal positions. 90

24. In a typewriting machine, the combination with the key levers, of a fulcrum bar having a depending knife edge with which said key levers engage and which forms a fulcrum therefor, a plurality of curved 95 springs each having one end secured in relatively fixed position with said fulcrum and having their opposite ends engaging respectively with the key levers, and a slotted member arranged adjacent said bar through 100 which the ends of said levers extend, said slotted member and said fulcrum bar co-operating to lock the key levers against removal when the same are in normal or depressed positions, but permitting the key 105 levers to be removed when they are swung to positions above their normal positions.

25. In a typewriting machine, in combination, a plurality of pivoted key-levers having free extremities movable downward and 110 upward from normal position, a common fulcrum for said levers, and means to maintain said levers and fulcrums in co-operative relation during pivotal movement of the former downward from normal position and 115 to permit removal of said levers from said fulcrum when the former are pivotally moved upward from normal position.

In testimony whereof I affix my signature in the presence of two witnesses.

JOSEPH ALBERT RONCHETTI.
